UNITED STATES PATENT OFFICE.

MERRITT GALLY, OF BROOKLYN, NEW YORK.

PRINTING-PRESS.

SPECIFICATION forming part of Letters Patent No. 430,281, dated June 17, 1890.

Application filed November 12, 1889. Serial No. 330,020. (No model.)

To all whom it may concern:

Be it known that I, MERRITT GALLY, residing at Brooklyn, in the county of Kings and State of New York, have invented certain new and useful Improvements in Printing-Presses, of which the following is a specification, reference being had therein to the accompanying drawings.

The invention relates to printing-presses; and it consists in the novel construction, arrangement, and combination of the parts, as hereinafter described.

In the accompanying drawings, Figure 1 is a side view, partly sectional, of the body of a printing-press, showing the devices for controlling the motion of the platen and the ink-distributing apparatus of the press in operating position. Fig. 2 is a face view of a part of the ink-distributing apparatus enlarged, and Fig. 3 is a face view of the impression-lock.

In my patent of November 9, 1886, No. 352,237, I describe and claim a plate, as A, Fig. 1, used as bed or platen of a press when supported upon a rocker or rockers, as R, and controlled in its movement by a link, as e; and in a subsequent application, Serial No. 263,864, filed February 13, 1888, I have described similar devices, except that the link was removed to a position back of the pivot of the draw-bar C and pivoted to a removable shoe, as H. In the present case the construction does not differ from the latter, except that the pivot-eye of the shoe H is located above the face of the rocker-seat S, instead of being on a line with the face of the rocker-seat. The position of the eye of shoe H, as shown in Fig. 1, is advantageous, as it increases the movement of plate A without increasing the throw of the impression draw-bars C.

In Fig. 1 plate A is shown in its impression position, and it will be seen that in this position the rocker R is prevented from lifting or being depressed at the heel by means of the link e, which in position shown forms a rear lock for plate A. The toe of rocker R is at the same time held down during its short sliding movement for the impression by means of the lock N. The two locks N and e

hold plate A practically parallel with plate B during the impression, so that a form may be worked "out of center" without slur.

To facilitate readjustment of the lock N in case of wear, I construct it as shown in Fig. 3. The lock N is shown as bolted to the projections of the rocker-seat D D'. As a convenient means of allowing for take-up, I place underneath the shoulders of lock N, which rest on the rocker-seat, a number of very thin washers W', (shown in exaggerated proportions, Fig. 3,) of hard paper or thin sheet metal, one or more of which may at any time be removed to make up for the wear of the lock or toe of the rocker. The removable shoe H allows also for take-up of any wear of the pivots of the link e, either by the insertion of washers or the grinding away of the plate or shoe H.

In Fig. 1 the roller for producing lateral change-distribution of the ink is shown at K as a metallic roller against a soft distributor d. The roller K may, however, if desirable, be a soft roller in contact directly with the distributing-cylinders V or T. The cylinders V T are supported in frame-work to the bed B in proper position for distributing the ink to be applied to the form F on bed B before the impression is made by plate A. Roller K is held in two slides f f', Fig. 2, which are supported in position in slideways W in the frame-work of the press, as shown in Fig. 1. Roller K is provided with a pinion t, and while it is revolving has a reciprocating lateral movement produced by means of a staggered gear-wheel b, which meshes into pinion t. The pinion t is provided with collars or flanges t' t', which are alternately in driving-contact with wheel b. I have already made application for patent for this feature, the staggered wheel b being pivoted to the hub of the slide f. I however show an improvement in the present case. Through the slides f f', I bore two holes exactly in line and parallel with each other. One of the holes in each of the slides forms the bearing for one of the journals of roller K. To the other holes I fit closely a rod Z. I then adjust the slides f f' exactly in line with each other, and

fasten them to the rod by means of pins or set-screws $n\ n$, as shown in Fig. 2. This construction prevents cramping of the gears $t\ b$ and secures an easy lateral motion to roller 5 K. Roller K is revolved by frictional contact with roller d or cylinder V, as the case may require.

The devices for the rocking motion and impression-locks may be applied to either the 10 bed or the platen of the press, or to both, as either plate A or B, or both, may have motion, as the case may require.

The impression movement may be produced by means of impression-cranks J—one for 15 each side of the press—or by any other suitable means.

What I claim as my invention is—

1. The bed or platen of the press, having a rocking motion and supported upon a rocker, 20 as R, in combination with the link, as e, for controlling the rocking motion, and the lock, as N, for holding the toe of the rocker firmly against the rocker-seat during the impression, substantially as set forth.
- 25 2. The combination of the platen having rockers attached, the rocker-seat, the lock for holding down and guiding the toe of the platen, and a lock connected to and guiding the heel of the platen during the final impression, substantially as described.
- 30 3. The combination, with the rocker-seat S and rocker R, of the lock, as N, applied to

the toe of the rocker and made adjustable to provide for wear, substantially as set forth.

4. The combination, with the bed or platen 35 of the press, supported upon a rocker or rockers, as R, and having a link, as e, pivoted to the heel of the rocker for controlling its rocking motion, of the shoe-eye, as H, having its pivot for the link situated above the rocker- 40 seat.

5. The combination, with the bed of the press and its supporting frame-work for the distributing apparatus, of the slide journal-bearings $f\ f'$ for the lateral distributer K, the 45 bearings $f\ f'$ being tied together by means of the connecting-rod, as Z, substantially as set forth.

6. The combination, with the journal-bearings, as $f\ f'$, of the lateral distributing-roller, 50 as K, and the rod Z, the journal-seats and holes for the rod Z being made parallel with each other in the pieces $f\ f'$ and firmly set in line by means of the pins or set-screws, substantially as set forth.

7. The combination, with the slides, as $f\ f'$, and roller K, with pinion t , of the rod Z and staggered wheel b, the rod Z forming the journal for wheel b, substantially as set forth.

MERRITT GALLY.
